UNITED STATES PATENT OFFICE.

FRANK E. SPRAGUE, OF NASHUA, NEW HAMPSHIRE.

TRIPLE-HOOK COLLAR-FASTENER.

1,140,541.

Specification of Letters Patent. Patented May 25, 1915.

Application filed August 15, 1912. Serial No. 734,939.

To all whom it may concern:

Be it known that I, FRANK E. SPRAGUE, a citizen of the United States, and a resident of Nashua, in the county of Hillsboro and State of New Hampshire, have invented 5 certain new and useful Improvements in Triple-Hook Collar-Fasteners, of which the following is a specification.

This invention relates to devices for attaching collars to shirts in somewhat the 10 manner of an ordinary collar-button.

As is well known, there are several objections to ordinary collar-buttons, one being that the circular disk, usually quite small, 15 is liable to create objectionable pressure and sometimes a pinching action of the skin at the back of the neck, another being that it produces a hump in the back of the collar, and another is that the ordinary collar-button 20 ton is likely to work loose and to become lost.

As substitutes for a collar-button, sheet metal clips have been made, having a base and a tongue to pass through the button-holes of the neck-band of the shirt and the 25 collar, but no such clip that I am aware of is adapted for use with the different styles of shirts hereinafter referred to.

The object of the present invention is to provide a simple and reliable collar-fastener 30 which is adapted to be used with any kind of a shirt, which cannot work loose, even when no collar is attached to the neck-band of the shirt, and which cannot cause any 35 discomfort or injury to the back of the neck of the wearer.

To these ends the invention consists in the improvements which I shall now proceed to describe and claim.

Of the accompanying drawings, Figure 1 40 illustrates my improved fastener as used in connection with the neck-band of a shirt which opens at the back, such type of shirt being commonly known as a bosom-front shirt. Fig. 2 represents a section on line 45 2-2 of Fig. 1, on a larger scale. Fig. 3 is a view similar to Fig. 2, illustrating the fastener as used in connection with a negligée shirt, which almost invariably opens at the front. Fig. 4 is a perspective view of my 50 improved fastener. Fig. 5 is an edge view, looking from the top. Fig. 6 is an elevation of the form of blank from which the fastener is made. Fig. 7 is a sectional view, illustrating the manipulation necessary to 55 remove the fastener from the neck-band of a shirt which opens at the back. Fig. 8

illustrates the manipulation necessary to place the fastener in position for use in connection with the neck-band of a shirt which opens at the back. Fig. 9 illustrates the 30 method of placing the fastener in position in the neck-band of a shirt that opens in front.

Similar reference characters indicate similar or the same parts in all of the views. 35

A bosom front shirt, the neck-band of which opens at the back, has one end of the neck-band made of a double thickness, the inner layer being to protect the back of the neck of the wearer from contact with the 40 collar-button. This inner strip of the neck-band is indicated at *a*, in Figs. 1, 2, and 7. The outer strip or flap *a'* has a button-hole, as usual. The other end of the neck-band, indicated at *a*², is of single thickness. 45 The base of the ordinary collar-button is fitted between the two strips *a*, *a'*, and the shank projects through the button-hole of the strip *a'*, and then the other end *a*², of the neck-band is buttoned over the button-head, projecting then to enter the button-hole of the collar *c*. The other, or negligée 50 type of shirt illustrated, comprises the inner fabric layer *b*, which usually has no button-hole, a short outer flap or layer *b'* 55 having a button-hole for the shank of a collar-button. I am able to employ my improved fastener with equal facility with either of these types of shirts. My improved fastener, made of metal or celluloid, 60 or other suitable sheet material, has a total distance from front to back less than what is ordinarily necessary for a collar-button, because of the flat surface presented, the ordinary collar-button having a head 65 which protrudes rearwardly considerably. As illustrated in Figs. 4, 5, and 6, the latter figure representing the blank for being bent to the form shown in Figs. 4 and 5, 70 comprises a base having a mid portion 10 and wide rounded wings 11, the wings being approximately circular in form. The mid portion 10 is relatively narrow, and projecting rearwardly from the lower edge of 75 said mid portion 10 is the flat shank 12, the 80 long hook or tongue 13 extending downwardly from said shank substantially in a plane parallel with the vertical plane of the base, the plane of the shank 12 being substantially at a right angle to the plane of 85 the base and tongue. Preferably, the tapered tip 14 of the tongue 13 is curved rear-

wardly, so that there will be no objectionable pressure brought against the back of the wearer if he throws his head upwardly. The base 10 and wings 11, as a whole, are 5 curved from end to end, as best shown in Fig. 5.

A most important feature of my invention is, that the upper end of the hook or tongue 13 is wider than the shank 12, presenting 10 shoulders 15 which act as hooks, as herein-after described.

When the fastener is used in connection with a shirt of the type indicated in Figs. 1 and 2 the strips a , a' are separated, as 15 shown in Fig. 8, and the fastener slid downwardly against the surface of strip a , to carry the tongue 13 through the button-hole of the strip or flap a' , said button-hole being slid along the tongue on to the shank 20 12. The width of the upper end of the tongue 13, including the shoulders 15, is preferably, such as to just snugly pass through a button-hole of the regulation length. Application of the fastener in the 25 manner described, holds it in position so that the other end of the neck-band a^2 can be buttoned over the tongue 13, as indicated in Figs. 1 and 2, the tongue 13 being then held in position to enable the button-hole 30 of the collar c to be readily passed upwardly along said tongue and past the shoulders 15 to the shank 12. There is never any liability of the collar coming off when so attached. When the collar is detached, 35 there is no liability of the neck-band of the shirt opening accidentally, because one end of one button-hole will be engaged by the shank 12 behind one hook or shoulder 15, and the other end of the other button-hole 40 will be engaged by the shank behind the other hook or shoulder 15. To unbutton the neck-band it is necessary to first pull the end a^2 outwardly, as indicated in Fig. 7, and slip it down off from the tongue 13, after 45 which the fastener can be removed by separating the strips a , a' , as shown in Fig. 8.

When the fastener is to be used in connection with a negligée shirt, such as illustrated in Figs. 3 and 9, the flap b' is pressed 50 outwardly, as indicated in Fig. 9, and the

tongue 13 is passed through the button-hole of said flap, and the fastener then turned to the position shown in Fig. 3, after which the collar c can be applied in the same manner as described in connection with Fig. 2. 55 When in this position, it cannot possibly work loose. It can only be removed by reversing the movements just described in connection with Fig. 9.

It will be now understood that I have provided a collar fastener suitable for use in connection with either kind of shirt or neck-band described, and that, owing to the three hooks presented by the members 13 and 15, there is no possibility of the fastener working loose. The hook 13 engages the collar c , and the hooks 15 engage opposite ends of the button-holes of the overlapping ends of the neck-band of a bosom front shirt. The fact that the shank 12 is at right angle to 70 the plane of the base and of the tongue 13, insures the retention of all of the parts or members designed to be connected by the fastener, as illustrated in Figs. 2 and 3.

I claim:

A collar fastener comprising a base having a narrow central portion the upper edge of which is substantially straight and wide rounded lateral wings, a straight shank extending rearwardly from the narrow portion of the base, and a buttonhole-engaging tongue having a tapered rearwardly curved tip extending downwardly from said shank, the entire base including the wings being vertically straight and laterally curved from 85 end to end to correspond to the curvature of the neckband of a shirt, the said shank being straight and flat from end to end, one end thereof meeting the base, and the other the tongue at substantially a right angle, the 90 upper end of the tongue being wider than the shank to form buttonhole-engaging shoulders.

In testimony whereof I have affixed my signature, in presence of two witnesses.

FRANK E. SPRAGUE.
